POWER AND GUIDING UNIT FOR POWER DRIVEN IMPLEMENTS

Byron L. Ertsgaard, Excelsior, and Stanley V. Sonmore
and Renhold J. Luger, Jr., Minneapolis, Minn., assign-
ors to Toro Manufacturing Corporation of Minnesota,
Minneapolis, Minn., a corporation of Minnesota

Application October 21, 1955, Serial No. 38,521

Term of patent 14 years

(Cl. D40—1)

FIG. 1

FIG. 2

FIG. 3

Fig. 1 is a perspective view of a power and guiding unit for power driven implements, taken from the front and right hand side showing our new design.

Fig. 2 is a perspective view of the same, taken from the front and left hand side thereof.

Fig. 3 is a rear elevational view of the same.

We claim:

The ornamental design for a power and guiding unit for power driven implements, as shown.
